UNITED STATES PATENT OFFICE.

MARTIN BRENNAN, OF GARRETSON, SOUTH DAKOTA.

HARROW.

No. 801,764.

Specification of Letters Patent.

Patented Oct. 10, 1905.

Application filed April 4, 1905. Serial No. 253,838.

To all whom it may concern:

Be it known that I, MARTIN BRENNAN, a citizen of the United States, residing at Garretson, in the county of Minnehaha, State of 5 South Dakota, have invented certain new and useful Improvements in Harrows; and I do hereby declare the following to be a full, clear, and exact description of the invention, such as will enable others skilled in the art to 10 which it appertains to make and use the same.

This invention relates to harrows, and more particularly to means for "dumping" harrows, by which is meant the operation of ridding the harrow-teeth of accumulations of vegetable growth, the object of the invention being 15 to provide means for automatically raising and dropping the harrow-frame during the progress of the implement.

In the drawings forming a portion of this 20 specification, and in which like numerals of reference indicate similar parts in the several views, Figure 1 is a rear elevation showing a harrow embodying the present invention. Fig. 2 is a vertical section taken longitudinally 25 through the harrow and showing the elevating wheel and rack in elevation and in active positions. Fig. 3 is a top plan view of the harrow. Fig. 4 is a view similar to Fig. 2 with the parts in inoperative position.

Referring now to the drawings, there is shown a harrow including a frame including the longitudinal beams 5 and 6 and transverse beams 7, the several beams being provided with the usual harrow-teeth 8. The front 35 ends of the longitudinal beams 5 and 6 are connected to a front transverse beam 9, to which are connected draft appliances 10 for hitching draft-animals to the harrow. Secured to the beams 5 and 6 are the forwardly- 40 directed ends of an arch 11, which stands in a vertical plane transversely of and in the rear of the harrow-frame. From the central portion of the arch there depends a standard consisting of a plate bent upon itself to form the 45 spaced arms 12 and 13 and the connecting-bight 14, which latter is riveted to the central portion of the arch. The arms 12 and 13 are slotted vertically, as shown at 15, and in these 50 slots are received the ends of an axle 16, on which is fixed a ground-wheel 17. With this arrangement it will be seen that the rear por-

tion of the harrow-frame with the arch and the standard may be raised and lowered, while permitting the wheel to run upon the ground.

To raise and subsequently drop the harrow-frame at times, the ground-wheel is provided with a pinion 18, which is fixed to the axle 16, so that it will rotate with the ground-wheel. Pivoted at its upper end against the upper portion of the inner face of the arm 12 of the 60 standard is a rack-bar 19, which is held normally with its lower end swung rearwardly by means of a helical spring 20, connected to the rack-bar above its pivot and to the standard. A rock-shaft 21 is mounted in the arch 65 and at one end is provided with a treadle 22 in position for engagement by the foot of the operator to rock the shaft in one direction. At the opposite end of the shaft is a depending arm 23, which is pivotally connected with 70 the lower end of the rack-bar in such position that when the treadle is depressed the rack-bar will be swung into engagement with the pinion that is carried by the ground-wheel. When the rack-bar engages the pinion at the 75 rear side of the latter, as illustrated, forward movement of the ground-wheel will cause the pinion to feed the rack-bar upwardly, so that the harrow-frame will be correspondingly raised, and the accumulations upon the teeth 80 will drop from the latter. When the lowermost tooth of the rack-bar has moved from engagement with the pinion, the treadle may be released, and the spring will serve to throw the rack-bar away from the pinion, and the 85 harrow-frame will drop to reengage its teeth with the ground. This operation may be repeated as often as may be desired to rid the teeth of the accumulated vegetation.

What is claimed is—

1. The combination with a harrow-frame provided with teeth, of a ground-wheel mounted in the frame and with respect to which the latter is vertically movable, a pinion carried by the ground-wheel, a rack-bar carried by 95 the frame and means for throwing the rack-bar into and out of engagement with the pinion.

2. The combination with a harrow-frame having teeth, said frame including an arch and a standard carried by the arch and comprising laterally-spaced arms having vertical slots,

of a ground-wheel disposed between the arms of the standard and having a shaft rotatably mounted in the slots of the arms and moving vertically therein, a pinion carried by the 5 ground-wheel, a rack-bar pivoted at its upper end to the standard and movable with its lower end portion into and out of engagement with the pinion, and means for moving the rack-

bar into and out of engagement with the pinion.

In testimony whereof I affix my signature in presence of two witnesses.

MARTIN BRENNAN.
